Attorney.

UNITED STATES PATENT OFFICE.

CHARLES A. NEARY, OF OAKLAND, NEBRASKA.

ELECTRIC VEHICLE LAMP.

Application filed November 26, 1926. Serial No. 150,835.

This invention relates to electric vehicle lamps, and particularly to headlights, spot lights and other similar lamps for automobiles and other traveling vehicles.

One object of my invention is to provide a headlight, spot light, or other similar light having a reflector, with a movable reflector shield normally forming a complementary part of the reflector, and which is arranged on the left hand side of the vertical center of the lamp and adapted to be swung toward the right hand side of the lamp in such a position as to cut off the light rays from the left hand side of the road and to cast the light rays toward the right hand side of the road and in front of the vehicle equipped with the invention, whereby the field of illumination may be restricted so as to prevent the blinding of the driver of an approaching vehicle on the left hand side of the road, while admitting of the full capacity of the light being obtained for illumination of the roadway at the right hand side of the road and ahead of the vehicle equipped with the invention.

Another object of the invention is to provide a light reflector means of the character described which will operate without dimming the light and restricting the field of illumination along that portion of the road being traveled by the vehicle equipped with the invention.

The invention consists of the features of construction, combination and arrangement of parts, hereinafter fully described and claimed, reference being had to the accompanying drawings, in which:—

Figure 1 is a fragmentary plan view of the front portion of an automobile provided with head lamps embodying my invention.

Figure 2 is a front elevation of the same.

Figure 3 is a central vertical section through the lamp.

Figure 4 is a section on line 4—4 of Figure 3.

Figures 5 and 6 are views showing the application of the invention to a spot light lamp.

Referring now more particularly to Figures 1 to 4, inclusive, of the drawings, 1 designates a headlight lamp comprising a casting 2 and having a reflector 3 surrounding

the lamp bulb 4, which bulb is mounted in the usual socket 5.

Formed in the reflector 3 is a sector-shaped opening 6 which is arranged at the left hand side of the lamp 4, that is to say, on the left hand side of the vertical center of the headlight. This opening 6 is of a shape to receive a pivoted reflector shutter 7, of a sector shape conforming to that of the opening 6. The inner curved edge 8 of this shutter 7 is centrally hinged or pivoted to the stationary reflector 3, as at 9, in close proximity to the socket 5 at the center of the latter, while the outer edge 10 of the shutter 7 is located well forward of a transverse line intersecting the forward end of the bulb 4 so as to admit of its being swung for a light deflecting action in advance of the forward end of the bulb. The shutter 7 may be made of the same material as the reflector 3 and has an inner light reflecting surface 11 conforming to the reflecting surface 12 of the reflector 3. The concavo-convex shape of the shutter 7 also conforms with that of the reflector 3, so that when the shutter is swung back into the opening 6 it lies in the plane of the reflector 3 and serves as a complementary part of said reflector 3, whereby, in the normal use of the lamp, an unbroken reflector of usual shape, and having all of its surfaces flush or lying in a common line of curvature, is provided

for projecting a full light beam ahead, as will be readily understood. This follows from the fact that the shutter when in normal position, i. e., occupying the opening 6, lies at the same distance from the bulb as the opposite right hand portion of the reflector 3, so that all opposed reflecting portions of the reflector 3 and shutter 7 are equally centered with relation to the source of light.

When on the other hand the shutter is swung inwardly, as shown in dotted lines in Figure 4, from the full line position therein shown, the rays of light from the lamp 4 and reflector 3 are cut off at the left hand side of the lamp except at points approaching the axis of the beam, so that the casting

of blinding rays upon an approaching vehicle at the left hand side of the road will be prevented, while those rays projected at the left near the center of the beam will

be cast a sufficient distance in rear of the approaching vehicle in its direction of travel as to prevent annoyance to the driver thereof. While this restriction of the lateral illuminating field occurs, it will be noted that there is no dimming action of the light beam, so far as illumination for the benefit of the driver of the vehicle equipped with the invention is concerned, as the light rays cut off at the left hand side are simply diverted or reflected straight ahead and toward the right hand side, so that a full beam illumination of that portion of the road along which the vehicle equipped with the invention is traveling for the benefit of the driver of such vehicle. My invention thus avoids the well known objections to dimmers as heretofore suggested arranged within a lamp above the bulb and designed to be swung downward upon the bulb to deflect the light down upon the road, such dimmers in normal position reducing the reflecting area of the lamp and when in projected position cutting down the illuminating field for the driver of the vehicle to a dangerous degree. For the purpose of enabling the shutter 7 to be so shaped and mounted as to close within and normally form a part of the surface of the reflector 3, while at the same time adapting it to effectually perform its intended function, I provide the free or swinging edge 10 of the shutter with a light obstructing flange 11. This flange projects inwardly at right angles to the body of the shutter so as to increase its extent of projection into the path of the light beam, without the necessity of making the shutter objectionally wide, said flange acting, when the shutter is swung inwardly to deflecting position, to cut off those light rays at the left of the center of the light beam which would otherwise be deflected at such a sharp angle as to be liable to cause an objectionable degree of light to be cast into the path of travel of an approaching vehicle or into the eyes of the driver of such vehicle when the vehicles are at a certain distance apart, within the normal blinding range of the light beam.

The shutter 7 is adapted to be swung to light deflecting position by means of a lever arm 12, attached to the rear side of its hinged edge, and the deflector is adapted to be automatically returned to normal position and held within the opening 6 by means of a coiled spring 13. The lever arm 12 and spring 13 are housed in the space or chamber between the casing 2 and rear side of the reflector 3, and one end of the spring 13 is fastened to the shutter 7 and its other end to the lamp socket 5. In the adaptation of the invention to automobile headlights arranged at opposite sides of the vehicle, an operating shaft 14 is extended transversely of the vehicle through the engine housing in

rear of the radiator and journaled in the side walls of said housing, said shaft being provided at a central point with a crank arm 15 and having its extended ends beyond the housing provided with crank arms 16. To the crank arms 16 are attached rods or cables 17 which pass through openings 18 in the headlight casings 2 and are attached to the lever arms 12 of the headlights. An actuating rod 19 is connected to the crank arm 14 and extends rearwardly through the engine housing and instrument board in which it is slidably mounted, the rear end of said rod being provided with a suitable handle whereby it may be manipulated. By the use of this actuating mechanism the shutters 7 of both lamps may be swung from their closed positions at the left hand sides of the vertical centers of the headlights within which they are arranged toward the right hand side of the vehicle so as to cast the light rays towards such side of the vehicle and away from the left hand side of the road, the light beams, without being dimmed, being thereby projected and concentrated upon the right hand side of the road and that portion of the road directly in advance of the vehicle on which the headlights are mounted. As a result the driver of an approaching vehicle running in the opposite direction on the left hand side of the road will be entirely shielded from the light rays of the headlights equipped with the invention, while the driver of the vehicle provided with such headlights will be given the benefit of a full illumination of the road ahead of him.

In the adaptation of the invention to spot lights or other similar lights as shown in Figures 5 and 6, the reflector 3^a of the spot light is provided with an opening 6^a and shutter 7^a, closed by a spring 13^a and opened by a lever arm 12^a of the construction previously described. The spring and lever arm in this case may be exposed, but it is preferable under such conditions to provide the spot light with a casing 2^a enclosing the shield and also enclosing and protecting the lever arm and spring of the shutter. The spot light may be provided with the usual bracket mounting 21 for securing it upon the desired part of the vehicle, and this bracket mounting may be of any construction suitable for mounting the spot light inside or outside the vehicle. The lever arm 12^a of the spot light may be operated, if the spot light is arranged within the vehicle, by a pull cord or cable 22, and in the event that the spot light is arranged outside the vehicle the cord or cable may be extended from the point of attachment of the spot light to a convenient point so as to be operated by the driver occupying his seat in the driver's compartment. The operating means may, of course, in case of either the

headlight construction or the spot light construction, be varied in construction as required according to conditions in the use of such lights upon different types or constructions of vehicles.

Having thus fully described my invention, I claim:—

1. An automobile lamp having a reflector surrounding a light source centrally arranged therein, said reflector being provided with an opening at one side of the source of light, a pivoted shutter curved to conform to the shape of the material displaced to form said opening and normally occupying said opening, so as to snugly fit within and close the same and form a complementary portion of the reflector, said shutter being movable toward the opposite side of the reflector to deflect the light rays in such direction, and means for opening and closing said shutter.
2. An automobile lamp having a reflector surrounding a central source of light, said reflector having an opening therein at one side of said light source, a reflecting shutter pivotally mounted to normally occupy said opening and form a part of the reflecting surface of the reflector and being movable inwardly across the path of the light

rays emanating from the light source on such side of the center of the reflector, a light obstructing flange formed at right angles to the shutter and extending across the free edges thereof, and means for opening and closing said shutter.

3. An automobile lamp having a reflector surrounding a source of light centrally arranged therein, said reflector being provided with an opening at one side of the source of light, a pivoted shutter curved to conform to the shape of the material displaced to form said opening and normally occupying said opening, the edge surface of the shutter snugly engaging the edge of said opening throughout to arrange the shutter in the plane of, and form a complementary part of the reflector, said shutter being hinged to the reflector body and movable toward the opposite side of the reflector to deflect the rays in such direction, a lever arm attached to the shutter, operating means connected with said lever arm, and a spring connecting the free end of said arm with a fixed portion of the lamp for normally holding the shutter closed.

In testimony whereof I affix my signature.

CHARLES A. NEARY.
